United States Patent Office

Des. 203,539
Patented Jan. 25, 1966

203,539

CASKET

Joseph E. Billman, 9834 N. 2nd Way, Phoenix, Ariz.

Filed Jan. 19, 1965, Ser. No. 83,493

Term of patent 14 years

(Cl. D19—1)

FIG. 1

FIG. 2

FIG. 3

FIG. 4

FIG. 5

FIG. 1 is a front perspective view of a casket showing my new design, in closed condition;

FIG. 2 is a similar view but showing the casket in open condition;

FIG. 3 is a rear elevational view of the casket as seen in FIG. 1;

FIG. 4 is a top plan view thereof; and

FIG. 5 is an elevational view of the end opposite that seen in FIG. 1.

The bottom, not shown, is plain and unornamented.

I claim:

The ornamental design for a casket, substantially as shown and described.
